(57) **CLAIM**

The ornamental design for a audio soundbar speaker, as shown and described.

DESCRIPTION

FIG. 1 is a front perspective view of the audio soundbar speaker showing the new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a back view thereof.

The broken lines shown in FIGS. 2 and 3 are included for the purpose of illustrating portions of the audio soundbar speaker that form no part of the claim.

1 Claim, 3 Drawing Sheets(56)
